LIGHTING DEVICE

Ernest R. Lundstrom, Worcester, Mass.

Application September 21, 1938, Serial No. 231,063

2 Claims. (CL 240—10)

My invention relates to lighting devices and more particularly to that type adaptable for use in connection with Christmas trees and the like.

One of the principal objects of my invention is to provide a lighting device so constructed and arranged as to be secured about the trunk of a Christmas tree or the like whereby to supply electric current from an input source to the groups of electric lamps mounted on the tree.

Another object of my invention is to provide a device of the character described so constructed and arranged as to provide a safe, efficient and reliable extension connected to an input source of electric power whereby various groups of electric lamps may be easily connected and disconnected thereto as desired.

A further object of my invention is to provide a device of the character described which is simple in construction, durable in use, and economical in manufacture.

Other objects and advantages will be apparent from the following description, appended claims and annexed drawing.

Referring to the drawing wherein like reference characters designate like parts throughout the several views:

Figure 1 is a side elevation of my invention, illustrating the latter as applied to the trunk of a Christmas tree or the like.

Figure 2 is a fragmentary front elevation of my invention on an enlarged scale.

Figure 3 is a detailed sectional view on the line 3—3 of Figure 2.

Figure 4 is a detailed sectional view on an enlarged scale taken on the line 4—4 of Figure 1.

In practicing my invention I provide a flexible electric power supply extension 5 arranged spirally about the trunk 6 of a Christmas tree and comprising a pair of coextending independently insulated electric conductors 7 fashioned with upper and lower end sections 8 and 9 respectively.

Said conductors, between said end sections, are fashioned with a plurality of spaced pairs of socket members 10, the members of each pair being embedded in a body 11 of insulating material fashioned about said conductors and said conductors engage said members and are connected thereto by soldering or the like. The members of each pair are isolated relative to each other and each of said members are of a split wall type and yieldably receive therein the headed prongs 12 of a connector plug 13 electrically connected to the wiring of a group of electric lamps 14, it being understood that various groups of said lamps are connected to the extension 5

through the medium of the socket members 10 and the respective plugs 13.

The upper end section 8 is provided with an extended portion 15 equipped with spaced snap fastener elements 16 for locking engagement with each other when the portion 15 is disposed about the upper end of the trunk 6 whereby to maintain the upper end of said extension secured to the trunk as clearly illustrated in Figure 1 of the drawing.

The lower end section 9 is provided with a plug 17 equipped with outwardly extending prongs 18 electrically connected to the conductor 7 and adapted for insertion within a receptacle (not shown) of an electric power supply line. The plug 17 is formed with a flexible portion 19 provided with an opening 20 for receiving therethrough a nail 21 or the like whereby to secure said plug and lower end of said extension fixed to the lower end of the trunk.

The members 10 together with the prongs 12 are of the well known snap fastener type and said members are provided on their outer ends with circumferentially extending flanges overlying the outer faces of the bodies 11 as clearly illustrated in Figure 4.

From the foregoing it will be apparent that I have provided a simple and efficient device adapted to be entwined about the trunk of a Christmas tree or the like whereby groups of electric lamps may be easily connected thereto or disconnected therefrom. It is to be understood that various changes and modifications may be resorted to in the arrangement and construction of the various parts of the invention without departing from the spirit of the invention or scope of the appended claims.

What I claim is:

1. A flexible electric power supply extension adapted for spiral disposal about a body and comprising coextending insulated conductors fashioned with end sections and a plurality of spaced pairs of socket members between said sections, said socket members of each pair isolated relative to each other and arranged to yieldably receive spaced headed prongs of a connector for a group of electric lamps, one of said end sections provided with a portion equipped with spaced fastener elements for locking engagement with each other when said portion is disposed about said body whereby to maintain said last mentioned end section connected to the latter, and means secured to said other end section for securing the latter to said body.
2. A flexible electric power supply extension

adapted for spiral disposal about a body and comprising coextending insulated conductors fashioned with end sections and a plurality of spaced pairs of socket members between said sections, said socket members of each pair isolated relative to each other and arranged to yieldably receive spaced headed prongs of a connector for a group of electric lamps, one of said end sections provided with a portion equipped with

spaced fastener elements for locking engagement with each other when said portion is disposed about said body whereby to maintain said last mentioned end section connected to the latter, and a plug connected to said other end section and equipped with means adapted to secure said plug to said body, said plug adapted to effect connection with a source of electric power.

5
